[57] **CLAIM**

The ornamental design for a fluid flowmeter housing for an automotive engine fuel metering system, substantially as shown and described.

DESCRIPTION

FIG. 1 is an end, top and right side perspective view of a fluid flowmeter housing for an automotive engine fuel metering system showing our new design.

FIG. 2 is a top plan view thereof;

FIG. 3 is a rear elevational view thereof;

FIG. 4 is a right side elevational view thereof;

FIG. 5 is a front elevational view thereof;

FIG. 6 is a left side elevational view thereof; and

FIG. 7 is a bottom plan view.
